PROGRESSIVE HOBBYHORSE

Richard W. Angert, Cincinnati, Ohio

Application July 28, 1941, Serial No. 404,324

2 Claims.

(Cl. 272—53)

My invention relates to a progressive hobby horse. It has to do, more particularly, with a toy hobby horse which is adapted to be moved forwardly when rocked by a child sitting thereon.

Hobby horses of the general type indicated have been provided in the past. These prior art hobby horses have usually been of a complicated structure and, therefore, too expensive to manufacture as a toy. Furthermore, they have usually been of such a structure that considerable effort is required to move them forward. Also, they have been of such a nature as to result in injury to a child using them, for example, by pinching fingers between moving parts. Another disadvantage of these prior art hobby horses is that they have a tendency to tip during use which might cause injury to the child. Prior art hobby horses have also possessed other disadvantages.

One of the objects of my invention is to provide a hobby horse which will be moved progressively in an efficient manner with little effort by the child sitting thereon merely rocking it.

Another object of my invention is to provide a hobby horse of the type indicated in the preceding paragraph which is of a very simple structure and can be made of inexpensive materials so that the unit can be manufactured as an inexpensive toy.

Another object of my invention is to provide a hobby horse of the type indicated which is of a sturdy construction so that it will hold up under hard usage and which is substantially free of parts subject to excessive wear.

Another object of my invention is to provide a hobby horse of the type indicated which will not readily tip during use.

Another object of my invention is to provide a hobby horse of the type indicated which is of such a nature that there will be little danger of injury to the child using it.

Various other objects will be apparent herein-after.

In its preferred form my invention contemplates the provision of a hobby horse including a main body carried by suitable wheels. This body has a rocking member pivoted for rocking movement in a vertical plane and upon which the child is adapted to be seated. This rocking member carries at its rear end a rearwardly and downwardly inclined tail or propelling member which is pivoted thereto and which has a friction member contacting with the ground. By rocking the rocking member, the friction mem-

ber on the propelling member is caused to contact with the ground at successive forwardly spaced points, thereby propelling the wheeled body portion along the ground.

5 The preferred embodiment of my invention is illustrated in the accompanying drawings wherein similar characters of reference designate corresponding parts and wherein:

Figure 1 is a side elevation, partly broken away, of a hobby horse made according to my invention.

Figure 2 is a plan view, partly broken away, of the structure shown in Figure 1.

Figure 3 is a sectional view taken substantially along line 3—3 of Figure 1 showing the pin for connecting the rocking member to the body portion.

Figure 4 is a perspective view of my hobby horse.

20 Figure 5 is a horizontal sectional view taken substantially along line 5—5 of Figure 1 and showing the steering means.

Figure 6 is a more or less diagrammatic view of my hobby horse showing the rocking member in forward position.

Figure 7 is a similar view but showing the rocking member in its rear position.

With reference to the drawings, I have illustrated my hobby horse as comprising a main body portion 1 carried by wheels and a rocking member 2 carried by the body portion 1.

The body portion 1 is composed of a pair of spaced vertically disposed longitudinally extending plates 3. These plates 3 are secured together and held in laterally spaced relationship by means of a bar 4 which extends longitudinally thereof. This bar 4 is disposed between the plates 3 adjacent the lower edges thereof and is bolted thereto by means of the bolts 5 which pass through any of a plurality of sets of openings 6 in the members 3. The bar 4 extends longitudinally substantially the full length of the members 3 and is in substantially horizontal position. The members 2, 3 and 4 may be made of wood or any other suitable cheap material.

Each of the members 3 has secured to its outer surface adjacent its rear end a bracket 7. This bracket is preferably bolted to member 3, as at 8, and extends downwardly and outwardly. As shown in Figure 2, the heads of the bolts 8 are countersunk on the inner surface of member 3, as indicated at 9, to prevent interference with member 2, as will be apparent hereinafter. The lower end of the bracket 7 is provided with an opening for receiving the reduced end 10 of an axle

member 11. A wheel 12 is rotatably mounted on each portion 10 of the axle and is secured in position by means of a washer 13 and a cotter key 14. The brackets 7 are preferably resilient so as to serve as springs.

At their forward ends, each of the members 3 has a forwardly and downwardly extending leg 15 bolted thereto by means of bolts 16. As shown in Figure 2, the heads of these bolts 16 are also within recesses, as indicated at 17, to prevent interference with member 2. A brace 18 disposed in front of members 3 is connected to the two members 15 and to members 3, as indicated best in Figure 4. Each of the legs 15 is provided with a horizontal slot 19 at its lower end. These slots receive the ends of axle 20 which projects therethrough. This axle 20 carries a wheel 21 which is disposed between the legs 15. The wheel 21 is held in position on the axle 20, as shown in Figure 5, by means of spaced collars 22 held in position by means of cotter keys 23. Each of the slots 19 has disposed therein on opposite sides of the axle 20 compression springs 24 which oppose each other and tend to maintain the axle 20 midway between the ends of the slot 19. The extensions of the axle 20 serve as foot rests for a child on the hobby horse. Flat spring members 25 carried by axle 20 at the inner and outer sides of member 15 and held in position by cotter keys 26 close the slots 19.

The rocking member 2 is disposed between the spaced members 3 and has its lower edge resting on the bar 4. The member 2 is in the form of a vertically disposed plate having a curved lower edge 27. This edge 27 is curved to a suitable extent to permit rocking of member 2 on the bar 4. However, if desired, the member 4 may also be curved in a reverse direction relative to edge 27 to produce a greater extent of rocking. The member 2 is provided with a seat 28 secured to the upper edge thereof and with a head portion 29 having handholds 30 carried thereby. The member 2 is secured to the body portion 1 by means of a pin 31 which extends laterally thereto and which extends into arcuate slots 32 formed on the interior of the members 3. Thus, rocking of member 2 relative to members 3 is permitted but relative longitudinal movement of member 2 and members 3 is precluded.

In order to move the hobby horse forwardly upon rocking of member 2, I provide the tail member or propelling member 33. This member 33 is in the form of a bar or rod which has its upper end pivotally connected to the rear and upper portion of the member 2, as at 34. This bar extends downwardly and rearwardly and has a ground-engaging member or block 35 secured to the lower end thereof. This block may be provided with a roughened or other type of friction surface 36 adapted to engage the ground. The member 33 is of such length that when member 2 is in normal position, the member 36 will contact with the ground a considerable distance behind the wheels 12.

In using this hobby horse a child will straddle the horse and sit on the seat 28 with his feet resting on the projecting portion of the axle member 20. If the child rocks the member 2 forwardly in the manner illustrated in Figure 6, the

rear end of member 2 will be raised pulling the rod 33 upwardly and forwardly and causing member 36 to contact the ground at a point closer to the wheels 12. Then if the member 2 is rocked backwardly, as shown in Figure 7, the member 36 will more firmly engage the ground and the wheeled body portion 1 will be forced forwardly. Steering of the hobby horse may be accomplished with the feet by pushing on the proper extension of the axle 20 which will be permitted by the springs 24. However, the springs 24 will return the wheel 21 to neutral position when the uneven pressure on the extensions 20 is released.

As previously indicated, I provide a plurality of sets of openings 6. Consequently, by positioning the bolts 5 in these different sets of openings the bar 4 may be adjusted to different vertical positions between members 3. This will vary the height of member 2 and the seat 28 carried thereby so that the hobby horse can be used by children of different sizes.

It will be apparent from the above description that I have provided a hobby horse having many advantages. The hobby horse can be moved forwardly with little effort. It will not readily tip during use and is of such a nature that it will not injure a child using it. It is of a simple construction and can be manufactured at a low cost but yet is of a sturdy structure and has no parts subject to excessive wear.

Various other advantages will be apparent from the preceding description, the drawings and the following claims.

Having thus described my invention, what I claim is:

1. A hobby horse of the type described comprising a wheeled body portion, said wheeled body portion comprising a pair of vertically disposed plates joined together adjacent their lower ends by means of a bar disposed therebetween, a rocking member comprising a vertically disposed plate disposed between said pair of plates; said rocking member being connected to the pair of spaced plates by means of an interfitting pin and arcuate slot construction, said rocking member having a curved lower edge contacting with said bar, and a propelling member pivotally connected to the rear end of said rocking member and extending downwardly and rearwardly therefrom, said member having a friction portion on its lower edge adapted to engage the ground.

2. A hobby horse of the type described comprising a wheeled body portion, said wheeled body portion comprising a pair of vertically disposed plates joined together adjacent their lower ends by means of a bar disposed therebetween, said bar being adjustable to different vertical positions between said pair of plates, a rocking member comprising a vertically disposed plate disposed between said pair of plates, said member having a curved lower edge contacting with said bar, and a propelling member pivotally connected to the rear end of said rocking member and extending downwardly and rearwardly therefrom, said member having a friction portion on its lower end adapted to engage the ground.

RICHARD W. ANGERT.
